(57) **CLAIM**
The ornamental design for a "stroller wheel," as shown and described.

DESCRIPTION

FIG. 1 is a front and right side perspective view of a stroller wheel, showing our new design, according to one embodiment;

FIG. 2 is a rear and left side perspective view of the stroller wheel shown in FIG. 1;

FIG. 3 is a front elevational view of the stroller wheel shown in FIG. 1;

FIG. 4 is a rear elevational view of the stroller wheel shown in FIG. 1;

FIG. 5 is a top plan view of the stroller wheel shown in FIG. 1;

FIG. 6 is a bottom plan view of stroller wheel shown in FIG. 1;

FIG. 7 is a right elevational view of the stroller wheel shown in FIG. 1;

FIG. 8 is a left elevational view of the stroller wheel shown in FIG. 1;

FIG. 9 is a second front elevational view of the stroller wheel shown in FIG. 1; and,

FIG. 10 is a cross-sectional view of the stroller wheel taken along line 10-10 of FIG. 9.

The subject matter shown in dashed lines is for illustrative purposes and forms no part of the claimed design.

1 Claim, 10 Drawing Sheets
